FOOT PEDAL OPERATED SHOVEL TOY

Austin S. Byrne, Freeport, N. Y.

Application April 21, 1947, Serial No. 742,877

3 Claims. (CL. 214—132)

1

This invention relates to toys and more particularly to those of such size that a child can be supported upon the same.

It is an object of the present invention to provide a toy which a child can operate by use of his feet and hands and which is particularly adapted for use in playing in a sand pile wherein all of the operations necessary for effecting a lifting and digging of sand material with a mechanical derrick can be effected by hand by the child when playing with the same.

It is another object of the present invention to provide a foot operated device for excavators of the type adapted to dig and lift sand or other loose material which can be operated in one direction to effect the lifting of the bucket and when operated in the opposite direction, will serve to release the hoisting chain extended over the lifting device so that the bucket can drop to the initial starting position to pick up another bucket full of sand.

Other objects of the present invention are to provide a sand pile toy of the mechanical type which is of simple construction, made of durable parts and not easily destroyed, and which will give considerable pleasure to a child in that both hands and feet are used in effecting the operation of this device.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of the toy embodying the features of the present invention with the shovel extended to the down position.

Fig. 2 is a top plan view of the toy.

Fig. 3 is a cross sectional view taken on line 3—3 of Fig. 2 looking in the direction of the arrows thereof.

Fig. 4 is a perspective view of the shovel with the trap door in the open position.

Fig. 5 is a view similar to Fig. 4 but with the trap door in the closed position.

Fig. 6 is an enlarged cross sectional view taken through the winch device on line 6—6 of Fig. 1 looking in the direction of the arrows thereof.

Fig. 7 is a side elevational view of the winch device showing the friction disc with openings therein into which is extended a detent as a means for safety and to retain the friction disc while the shaft is threaded through to engage the hoist chain drum.

2

Fig. 8 is a cross sectional view taken on line 8—8 of Fig. 7 showing the detent device for retaining the winch in the different positions, looking in the direction of the arrows thereof.

Fig. 9 is a horizontal sectional view taken on the line 9—9 of Fig. 7.

Referring now to the figures, 10 represents a base on which there is mounted a vertical support 11 with a seat 12 thereon adapted to be occupied by the child using the device. The support 11 has two forward legs 13 between which is extended a winch device 14 to be described more in detail hereinafter.

On the top of the support 11 is a wear plate 15 on which is pivotally mounted a rotating carriage base 16 formed of sheet metal and arranged to have parallel ends 17 between which is pivoted a bell crank hand lever 18 having a handle 19 thereon. This lever has an upstanding arm 21 to which is connected a pair of links 22 having turned down forward ends 23 which are pivotally connected to a pivot block 24. The pivot block 24 is slidably positioned on a boom 25 pivotally connected at one end to the carriage 16 so that it can be moved up and down as the bell crank 18 is operated. Raising the bell crank 18 regulates the depth of digging and holds or forces the bucket into the material being handled. When the bell crank is up to its position of maximum height, the connecting links knuckle over and lock the boom 25 in its lowest position causing the bucket to fill when advanced through the material. Without this feature, the bucket has a tendency to lift and slide over the material without having filled the bucket.

Depending from the pivot block 24, there is pivotally connected a shovel arm 26 on the outer end of which there is fixed by means of bracket elements 27 a shovel bucket 28 formed of sheet metal and having an open end 29 and a bottom end 31 adapted to be closed by a trap door 32 which is retained in the closed position by a bolt or latch 33 engaging with an opening 34 of a strap 35 on the side of the shovel bucket. As the latch 33 is pulled, the trap door will be released and the supply of material within the shovel bucket will drop out of the bottom thereof in the usual manner. A rope 37 is extended over a pulley 38 on the pivot block 24 and is tied to a hook 39 on the carriage 16 where it will be accessible to the child operating the toy.

The shovel bucket has a pulley wheel 41 thereon over which is extended a chain 42 anchored to the upper end of the boom 25, as indicated at 43, and after being extended over the pulley 41, it extends upwardly over a pulley 44 on the top of

the boom and thus rearwardly through the legs 13 of the support 11 for connection to the winch device 14. As the winch device is operated, the shovel bucket will be raised to pick up a load of sand. Thereafter this load can be turned to any position within 180° by the bell crank arm 18 and the boom 25 also can be raised by this same bell crank lever so as to properly position the shovel bucket to the place of disposal of the sand.

Preferably the chain 42 is extended into the rotating carriage base 16 and downwardly through an opening 45 within a sleeve 46 which serves to pivotally connect the rotating carriage base to the plate 15. A spring 46a is connected between the shovel arm 26 and the boom 25 and will tend to retain the shovel in the lowered initial digging position and place a tension upon the hoisting chain 42. This spring pulls the bucket arm back past the center of the pivot thus placing it in the most advantageous position to start filling the bucket.

Referring now particularly to Figs. 6, 7 and 8, a detail description will be made of the winch device. This winch device is adapted to be operated by pedal cranks 48 and 49 which can be reached by the child's feet so that the same can be turned to cause the chain 42 to be rolled up upon the same and to cause the lifting of the shovel bucket. However, this winch device is constructed so that upon reverse turning movement of the pedal crank the chain drum 68 will be automatically released and the shovel will quickly drop to the down position, assisted by the tension spring 43a. The end of the chain 42 is connected to a loop 69 on the drum 68, as shown in Fig. 6.

This winch device comprises a central shaft 51 having a threaded portion 52 thereon and to the opposite ends of which are connected the pedal cranks 48 and 49. This shaft has a fixed collar 53 thereon against which reacts a spring 54 to normally urge the shaft 51 to the left as viewed in Fig. 6. The shaft at the right side is journaled in a bearing block 55 with which the spring 54 engages. This bearing block is fixed to a bracket arrangement 56 secured to one of the legs 13. At the opposite side of the device, there is provided a two part bearing 57. This two part bearing 57 is connected by angle pieces 59 to the other of the legs 13.

Also on the threaded portion 52 of the shaft 51 is an internal threaded friction disc 61 having a radially extending flange forming a pawl ring 62 with holes 63 therein and circumferentially spaced therearound adapted to engage a spring-pressed detent 72 slidably projected from a suitable stationarily mounted casing 71.

Between the internal threaded friction disc 61 and the fixed collar 53 is disposed a chain drum 68 to which the hoist chain is anchored by a fastening screw 69.

Upon rotating the shaft 51 in the forward or hoisting direction, with the internal threaded friction disc 61 being retained by the detent 72, the shaft 51 and fixed collar 53 will thread forward through the friction disc 61 thereby causing the hoisting chain drum 68 to be retained tightly between the fixed collar 53 and the friction disc 61. When this retaining effort exceeds the pressure of the detent on flange 62, then the friction disc 61, shaft 51 and chain drum 68 will rotate as a unit winding the hoisting chain 42 on the chain drum 68, thereby causing the bucket to be lifted.

Also on the bearing 57 there is secured the de-

tent casing 71 which is adjustable toward or away from the pawl ring on flange 62 of the internal threaded friction disc 61 to present a detent extension to the openings 63 whereby to hold the friction disc 61 while the threaded portion 52 of shaft 51 is threaded through it to retain or release the drum 68. The pawl is beveled so as to release the friction disc 61 on the forward rotation and also to present a positive stop on the friction disc 61 in the reverse rotation to release the chain drum 68.

This detent device is threaded so that it can be adjusted to the proper position for engagement with the pawl ring on flange 62.

Upon a slight reverse rotation of shaft 51 by the pedal cranks, the same with fixed collar 53 will unthread through and away from the friction disc 61 which is locked against turning by the detent 72, thus releasing drum 68 and allowing it to rotate freely on shaft 51, whereby the hoisting chain 42 is unwound off the drum by the weight of the bucket returning to the down position assisted by the spring 46.

The release action to lower the bucket is obtained by a slight reverse rotation of the pedals. In this release action, the detent 72 acts as a positive stop on the threaded friction disc 61 thus retaining it while the threaded part 52 of the shaft 51 unthreads through it, thereby releasing the drum 68 which was held tightly between this friction disc 61 and the fixed collar 53 on the shaft 51, during the hoisting operation. Drum 68 is now free to rotate on the shaft 51 thereby allowing the hoisting chain to unwind from the drum as the bucket descends to its starting position.

The detent 72 acts as an additional safety feature in that it retains the winch in any position thus preventing the pedals from rotating backwards in the event the child removes his feet from the pedals while the bucket is suspended.

By pedaling forward again after finishing this releasing action, the winch device will act as a brake and stop the bucket in any position, then further forward pedaling will engage the hoisting drums tightly thereby raising the bucket.

It should now be apparent that there has been provided a toy for use by children which will cause the arms and legs to be coordinated while playing with the device and whereby the child will be instructed in the various operations of a derrick.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A child's toy in the form of a mechanical shovel comprising a base, an upstanding support 65 on the base, a rotating carriage base mounted on the support for lateral swinging movement, a boom on the rotating carriage base, a pivot block on the boom, a shovel bucket arm, with a shovel bucket thereon, extending downwardly 70 from the boom and the shovel bucket arm being pivotally connected to the pivot block, a chain operatively connected to the shovel bucket and extended upwardly to the end of the boom and rearwardly along the length of the boom, a foot 75 operated pedal crank device having a winch con-

nected with the chain to effect the lifting of the shovel bucket as the pedal cranks are rotated forwardly, said pedal device further including a 5
detent device for retaining the winch and the shovel bucket in any one of the positions to which they have been operated in one direction, said winch device including friction elements adapted to be brought automatically into tight engagement with one another as the pedals are operated to raise the shovel bucket and adapted to be automatically released to release the winch and the shovel bucket when the device is rotated in the opposite direction.

2. A child's toy in the form of a mechanical shovel comprising a base, an upstanding support on the base, a rotating carriage base mounted on the support for lateral swinging movement, a boom on the rotating carriage base, a pivot block on the boom, a shovel bucket arm, with a shovel bucket thereon, extending downwardly from the boom and the shovel bucket arm being pivotally connected to the pivot block, a chain operatively connected to the shovel bucket and extended upwardly to the end of the boom and rearwardly along the length of the boom, a foot operated pedal crank device connected with the chain to effect the lifting of the shovel bucket as the pedal cranks are rotated, said rotating carriage base being formed of strap material and having parallel upstanding end portions, bell crank pivoted between the end portions, links connected between one arm of the bell crank and the pivot block on the boom whereby upon raising and lowering the bell crank lever the boom can be raised and lowered, said bell crank lever also serving as handle means by which the rotating carriage base can be rotated laterally on the vertical support, said vertical support having a seat thereon, said winch device being mounted on the vertical support ahead of the seat whereby it can be reached with the child's feet, and said bell crank lever having a handle portion extending rearwardly to be accessible to the child when seated on the seat.

3. A child's toy in the form of a mechanical

shovel comprising a base, an upstanding support on the base, a rotating carriage base mounted on the support for lateral swinging movement, a boom on the rotating carriage base, a pivot block 5
on the boom, a shovel bucket arm, with a shovel bucket, thereon extending downwardly from the boom and the shovel bucket arm being pivotally connected to the pivot block, a chain operatively connected to the shovel bucket and extended upwardly to the end of the boom and rearwardly along the length of the boom, a foot operated pedal crank device connected with the chain to effect the lifting of the shovel bucket as the pedal cranks are rotated, said rotating carriage base being formed of strap material and having parallel upstanding end portions, a bell crank pivoted between the end portions, and links connected between one arm of the bell crank and the pivot block on the boom whereby upon raising and lowering the bell crank lever the boom can be raised and lowered, said bell crank lever also serving as handle means by which the rotating carriage base can be rotated laterally on the vertical support, means for regulating the depth of digging and holding or forcing the shovel bucket into the material being handled, locking means for said boom in its lowest position permitting said shovel bucket to fill when advanced through the material.
